JET EJECTOR FURNACE

Frederic O. Hess, Philadelphia, Pa., assignor to
 Selas Corporation of America, Philadelphia,
 Pa., a corporation of Pennsylvania

Application January 2, 1947, Serial No. 719,662

6 Claims. (Cl. 263—6)

1

The present invention relates to work heating furnaces and particularly to continuous furnaces of a type adapted for use in heating small metallic articles, or work pieces, up to a relatively high temperature as the articles are progressively advanced through a furnace heating zone from a charging station or furnace inlet to a discharging station or furnace outlet.

The general object of the invention is to provide improved means for ejecting heated articles from the furnace in which they are heated. A more specific object of the invention is to provide a continuous furnace of the above-mentioned type with a work ejector in the form of a fluid fuel burner located in the discharge station portion of the furnace, and means for operating said burner to eject each article when moved into a predetermined discharge position by then discharging a high velocity jet of hot gaseous material against the article. Advantageously, the force of the jet impinging against each article to be ejected, is great enough to move the article off the travelling carrier and into a discharge chute or other device through which the article moves away from the furnace.

In the preferred form of the present invention hereinafter described, the work ejection burner is of the type disclosed and claimed in my prior Patent 2,367,119, granted January 9, 1945, and comprising a combustion chamber and a wall having a restricted outlet formed wholly or largely of refractory material, and into which combustible fluid and air for combustion are supplied to maintain the desired combustion chamber pressure. In said preferred form of my invention, the said ejector burner forms part of the furnace heating system and is advantageously associated with means for quickly varying the pressure maintained in the combustion chamber of the burner, so that the burner may be operated to maintain the relatively high combustion chamber pressure needed for work ejection purposes during the brief recurring periods in which the heated work pieces or articles are ejected from the furnace, and may be operated with a lower combustion chamber pressure during the longer periods alternating with the work discharging periods.

During the intervals between successive work ejecting operations, the fluid passed into the combustion chamber of the ejector burner preferably consists of combustible gas and air premixed in substantially the proportions required for complete combustion. In some cases, the same mixture may be supplied at higher pressure during

2

the work ejecting operations. In other cases, the proportion of air to combustible gas supplied to the ejector burner may be substantially greater than is required for complete combustion at all times, or at least during the work ejecting periods. One effect of thus continuously or intermittently diluting the combustible mixture supplied to the ejector burner, is a reduction in the overall or average heating effect of the ejector burner, and the avoidance of overly large local heating effects, which may be injurious to the furnace and the work. Such heating effect reduction may be especially important where the work pieces are of relatively large size, and the work ejecting force must be correspondingly great.

The various features of novelty which characterize my invention are pointed out with particularity in the claims annexed to and forming 20 a part of this specification. For a better understanding of the invention, however, its advantages and specific objects attained with its use, reference should be had to the accompanying drawings and descriptive matter in which I have illustrated and described preferred embodiments of 25 the invention.

Of the drawings:

Fig. 1 is an elevation, partly in section, of an automatic furnace embodying the present invention, the section being taken on the broken line 1—1 of Fig. 2;

Fig. 2 is a horizontal section taken on the broken line 2—2 of Fig. 1;

Fig. 3 is a partial sectional elevation taken on the line 3—3 of Fig. 2;

Fig. 4 is a partial vertical section taken on the line 4—4 of Fig. 2; and

Fig. 5 illustrates a modified form of supply piping for the ejector burner.

40 The furnace structure shown in the drawings comprises a stationary furnace body A mounted on a stationary base or supporting structure B, and a rotary hearth C mounted on a rotating supporting structure D. The hearth C and its 45 supporting structure revolve about a vertical axis and the refractory body portion of the hearth structure forms a movable bottom wall of a furnace chamber E formed in the stationary body A of the furnace and extending circularly about 50 said axis. The chamber E is not a complete annulus, but is in the form of an arc of 325° or so, with its ends separated by a charging station F. As shown, the charging station F comprises a notch or space formed in the portion of the generally cylindrical stationary furnace body A above

the level of the hearth C, and extending from the periphery of the furnace body inward to the wall of a central vertical chamber G, and extending upward to the top of the furnace body portion A from the level of the top of the hearth C. The furnace body A and hearth C may be constructed in accordance with the usual practices of the furnace art, mainly of masonry, but ordinarily, and as shown, with an outer casing of sheet metal. The portions of the masonry exposed to high furnace temperatures may be formed of the usual refractory materials employed in so-called fire bricks and blocks or shapes, and other portions of the masonry may be formed of bricks or blocks of so-called insulating materials. No features of furnace construction and arrangement of the character just mentioned are claimed as novel herein, and as they may follow the usual practice of the art they need not be illustrated or described in detail herein.

As shown, heat is supplied to the furnace chamber E through furnace wall burners H mounted in burner openings H' formed in the roof of the chamber E, and receiving air and combustible gas, preferably premixed in the proportions required for substantially complete combustion, from branches I' of supply piping at the top of the furnace body A. The burners H may advantageously comprise suitably channelled bodies of refractory material with open combustion spaces at their lower ends, and are preferably of the type disclosed and claimed in my prior Patent 2,215,079, of September 17, 1940. With such burners, much of the heat generated is transmitted from the burners in the form of radiant heat.

The products of combustion of the combustible mixture supplied to the burners H pass away from the chambers E through vent channels J formed in the furnace body A. As shown in Fig. 4, the channels J have inclined lower end portions extending upwardly and outwardly away from the furnace chamber E at points distributed along the length of the latter and intermediate the burners H. The vertical upper portions of the vent channels J extend to the top of the furnace structure.

The rotary hearth C comprises an annular body of refractory material received in a slot formed in the furnace body A and extending circularly about the furnace axis, and extending downward from the bottom of the chamber E to the lower end of the furnace body A. The refractory portion of the hearth C is directly supported by a radially enlarged upper portion of a rotatable metallic supporting structure D. The latter comprises a center column D' mounted on a stationary base or pedestal DA to turn about the vertical axis of the furnace. As shown, the supporting structure D is normally maintained in continuous rotation by motor driven means comprising a speed reducing gear mechanism K. The latter includes a horizontal input shaft carrying a pulley K' driven through a belt K² by a driving motor K³. The speed reducing gear mechanism K includes a vertically disposed output shaft K⁴ carrying a spur gear K⁵ in mesh with a large diameter gear D² coaxial with and forming a part of the rotating hearth supporting structure D.

The rotary hearth C is provided with an upris- ing annular work support L suitably shaped to support the articles of work pieces M to be heated. As shown, the support L comprises vertically dis- posed refractory blocks having their lower ends

anchored in the body of the hearth C, and is formed with spaced radially extending notches L' at its upper edge. Each notch L' forms a cradle or seat in which a work piece M may be mounted with its axis extending radially away from the vertical axis of the furnace. The work pieces M may take various forms and be made of various materials, for example, they may be short steel cylinders which, after being heated, are

10 worked into valve parts by extrusion. While each work seat L' is being advanced by the rotation of the hearth through the charging station F, a work piece M may be placed therein manually, or by automatic feeding mechanism, not shown. Each work piece M after being mounted in the corresponding seat L' is moved by the rotation of the hearth C into the furnace chamber E, and through the major portion of the length of the latter and thence into the work ejection or discharge station or chamber N. The latter comprises an opening or space in the masonry of the furnace body A which extends across the furnace chamber from the inner wall of the latter to the peripheral portion of the furnace body. As shown, the discharge station N is separated from the adjacent side of the charging or loading station F by a relatively small angular distance.

When each work object passing into the discharging station reaches a predetermined position therein, it is subjected to the displacing action of a radially directed jet acting against the inner end of the work piece M and strong enough to move the work piece out of its supporting seat L'. In the form of construction shown, when each work object is thus displaced from its supporting seat L', it is moved into the upper inlet end of a downwardly inclined chute or guideway O having its lower discharge end at the outer side of the furnace body A. Advantageously, and as shown, the outer side of the ejection station space N is normally closed except for the passageway through the chute O by a wall portion M' which may form a separable part of the usual metallic casing surrounding the masonry of the furnace body A.

In the preferred form of the invention illus- trated, the fluid jet by which each work piece M is moved out of its seat L' and into the upper end of the chute O, is a jet of products of combustion, 50 which may sometimes be mixed with burning gases and which is discharged through the outlet P' from the combustion chamber P² of an ejector burner P. As shown, the burner P is horizontally disposed between the upper end of the discharge chute O and the central chamber G, and the axis of the outlet passage P' is horizontal and extends radially away from the furnace axis and may well be approximately coincident with the axis of the work piece M at the instant at which the pressure in the burner chamber P² is increased to move the work piece off its support L and into the discharge chute O.

As will be apparent, the means for supplying air and combustible fluid to the burner chamber P², and for regulating the pressure in that chamber, may take various forms. In the arrangement shown in Fig. 1, a preformed mixture of gas and air is continuously supplied to the inlet P³ of the burner P through a pipe Q at a pressure regulated by valve connections interposed between the pipe Q and a supply main QA. The pipe Q extends downward into the chamber G from a level above the top of the furnace to the level of the burner inlet P³. These valve con- nections between the pipe Q and main QA, as

shown in Fig. 1, comprise a pipe section including a throttle valve R and a second pipe connection including a cut-off valve S. The valve R is adapted to pass combustible mixture from the main QA into the valve chamber P² at any relatively low rate which may be found desirable for operation during the intervals between the periods in which the burner P is used as a work ejector. The relatively low rate at which the combustible mixture is then supplied through the valve R may be varied, and the normal low pressure in the valve chamber P² correspondingly varied, by adjustment of that valve. The valve S is mounted in a pipe section forming a by-pass about the valve R. The valve S is of a type adopted to be rapidly adjusted from a normally closed condition into a wide open condition. In its wide open condition the flow capacity of the valve S is sufficient to effect an almost instantaneous increase in the pressure in the burner chamber P² to the amount required to create a discharge jet effective to move the work piece M on which the jet impinges out of its seat L' and into the discharge chute O.

Advantageously, the valve S is automatically actuated to momentarily increase the pressure in the ejector chamber P² as each work support L is moved into position in front of the burner P. For example, the valve S may be operated through mechanical or electrical connections by the rotating structure D. Thus as diagrammatically shown, the valve S may be of the solenoid type biased to its closed position, and moved into its open position when the solenoid coil S' of the valve is energized by the closure of a control switch T effected by projections T' carried by the hearth rotating structure D. Each projection T' is disposed so as to close the switch T at the instant a corresponding work seat L' is brought into its discharge position.

The main QA may also supply combustible fluid mixture through a suitable pressure reducing valve to the piping I, and thereby to the furnace roof burners H which supply most of the heat utilized in heating the furnace chamber E. Alternatively, the valves R and S may receive combustible mixtures from separate mains or supply pipes. Thus, as shown in Fig. 5, for example, a main QB may supply combustible mixture at a relatively low pressure to the piping I through which the roof burners H are supplied, and to the inlet of the pipe section including the valve R, and a pipe QC may supply a combustible mixture at a higher pressure to the valve S. In such case, the valve R need not be adjusted to create a substantial drop in the pressure between the main QB and the pipe Q. The fluid supplied to the burner P through the valve S from the main QC may consist of air and gas mixed in the proportions required for complete combustion, or it may consist of a mixture of air and gas containing substantially more air than is required for the complete combustion of the gas, or in some cases the fluid supplied by the main QC may be air alone. Ordinarily, however, the fluids supplied to the burner chamber P² should be of a character to maintain combustion in the chamber at all times.

The furnace structure shown in the drawings may be widely modified in form and dimensions as the conditions of use make desirable. In the particular furnace form and design shown in the drawings, the full width of the furnace chamber E, shown at the left hand side of Fig. 1, is a little less than one-half foot, and the radial distance from the center of the furnace chamber E to the

furnace axis is about two feet. The hearth is provided with twenty-four work supports L, each adapted to support a work piece M in the form of a steel cylinder 1 inch in diameter and 1½ inches long, and the hearth C makes one revolution every four minutes so that work pieces M are normally ejected at ten second intervals. The furnace chamber E is so heated that in the period of a little more than three minutes required for the movement of each work body M through the furnace chamber E from the charging station F to the discharge station N, the work piece attains a forging temperature of approximately 2150° F. To this end, the temperature of the atmosphere in the chamber E may be maintained constant at about 2500° F.

As will be understood, the foregoing structural and operative data is given by way of example and illustration and not by way of limitation, and the dimension, temperatures and rate of operation may be widely varied as conditions make desirable. For example, to attain the same discharge temperature of 2150° F., the heating temperature or the heating period would have to be increased if the work pieces were steel cylinders 3 inches in diameter and 3 inches long, as they may be in some cases. Ordinarily, a furnace for heating articles of such size should have greater dimensions than those specified above. When the articles heated are made of a material other than steel, such for example as magnesium, the final temperature to which the article is heated, and its rate of heating, may be quite different from those desirably employed in heating steel articles.

To eject steel work pieces of the character above mentioned, the ejection pressure in the burner chamber P² may well be of the order of 2 pounds above the pressure of the atmosphere and the velocity of the jet discharged through the ejector burner may well be about 1200 feet per second. The jet force which must be applied to the work piece being ejected from the furnace increases, of course, with the weight of the work piece. An increase in the work piece weight may be taken care of by increasing the volumetric capacity of the burner so as to increase the amount of fluid discharged through the port P' without necessarily requiring any increase in the pressure in the chamber P² or in the jet velocity. However, an increase in the pressure in the chamber P² of a burner of given size, will increase the work discharging energy available in the jet discharged through the outlet of the burner.

In the use of the furnace and heat forging temperatures of the order of those mentioned above by way of example, provisions should be made for cooling parts as required, to avoid objectionable overheating. Thus, as indicated in the drawings, the masonry wall of the central chamber G in the furnace body may be provided with a wall lining U, and water walls U' may be provided at the vertical outer edges of the masonry portions at the sides of the charging station F, and the wall of the discharge chute O may be formed with water cooling passages.

To prevent air leakage or gas leakage through the joints between the abutting masonry portions of the rotating hearth C and furnace body A, inner and outer annular sand seals W and WA may be provided as shown in Fig. 1. As shown, the seal W comprises an annular trough W' supported by the portion of the stationary framework structure B directly beneath the central portion 70 of the kiln, and the seal WA comprises an annu-

lar trough W^2 carried by the rotating structure D. A metallic cylinder W^3 having its upper end attached to the rotating hearth structure adjacent the inner edge of the latter extends down into the trough W' of the seal W. Similarly, a metallic cylinder W^4 attached at its upper end to the stationary body portion of the furnace extends down into the outer sealing trough W^2 . Sand is supplied to the inner sealing trough W at the inside of the angle W^3 through inclined channels I formed in the stationary portion of the oven masonry, and open at their upper ends to the lower end of the central chamber G. Sand to maintain the outer seal may be passed into the outer trough W^2 through an inclined channel XA opening at its upper end into the charging station space F through the portion of the masonry at one side of said station. As shown in Fig. 1, a fire check Z is located in each of the pipe branches receiving combustible mixture from the main QA.

While in accordance with the provisions of the statutes, I have illustrated and described the best forms of embodiment of my invention now known to me, it will be apparent to those skilled in the art that changes may be made in the forms of the apparatus disclosed without departing from the spirit of my invention as set forth in the appended claims, and that in some cases certain features of my invention may be used to advantage without a corresponding use of other features.

Having now described my invention, what I claim as new and desire to secure by Letters Patent, is:

1. A furnace structure formed with a heating chamber and with a work piece discharge passage having its receiving end open to said chamber, heating means for said chamber including a fluid fuel burner structure having a combustion chamber with a restricted outlet opening into said heating chamber, and means for supplying combustible fluid to said combustion chamber at a relatively high pressure to thereby discharge through said restricted outlet a heated fluid jet adapted to move a work piece from said furnace chamber into said discharge passage.

2. A furnace structure formed with a heating chamber and with a work piece discharge passage having its receiving end open to said chamber, heating means for said chamber including a fluid fuel burner structure having a combustion chamber with a restricted outlet opening into said heating chamber, and means for intermittently supplying combustible fluid under a relatively high pressure to said combustion chamber to thereby effect the discharge through said restricted outlet of a heated fluid jet adapted to impinge against a work piece in said heating chamber and move said work piece into said discharge passage.

3. A furnace structure formed with a heating chamber and with a work piece discharge passage having its receiving end open to said chamber, heating means for said chamber including a fluid fuel burner structure having a combustion chamber with a restricted outlet opening into said heating chamber, means for supplying combustible fluid to said combustion chamber at a relatively low pressure, and means for intermittently supplying combustible fluid under a higher pressure to said combustion chamber to thereby effect the discharge through said restricted outlet of a heated fluid jet adapted to impinge against

a work piece in said heating chamber and move said work piece into said discharge passage.

4. A continuous furnace comprising a structure formed with spaced apart charging and discharging stations and with an elongated furnace chamber extending between said stations and having at said discharging station an outlet from said chamber for work pieces, a work conveyer operative to move work pieces through said chamber from said charging station to said discharge station, heating means for said furnace chamber including a fluid fuel burner located at said discharging station and comprising a combustion chamber with a restricted outlet directed toward the portion of the furnace chamber space occupied by each work piece when moved into said discharge station by said conveyor, and means for supplying combustible fluid to said combustion chamber at a relatively high pressure to thereby discharge through said restricted outlet a fluid jet adapted to move a work piece out of said furnace chamber portion and into said discharge passage.

5. A continuous furnace comprising a structure formed with spaced apart charging and discharging stations and with an elongated furnace chamber extending between said stations and having at said discharging station an outlet from said chamber for work pieces, work conveyor means operative to move work pieces through said chamber from said charging station to said discharge station, heating means for said furnace chamber including a fluid fuel burner located at said discharging station and comprising a combustion chamber with a restricted outlet directed toward the portion of the furnace chamber space occupied by each work piece when moved into said discharge station by said conveyor, and means including a supply valve opened intermittently by said work conveyor means for supplying combustible fluid to said combustion chamber at a relatively high pressure when said valve is open and thereby effect the discharge through said restricted outlet of a fluid jet adapted to move a work piece out of said furnace chamber portion and into said discharge passage.

6. A continuous furnace comprising a structure formed with spaced apart charging and discharging stations and with an elongated furnace chamber extending between said stations and having at said discharging station an outlet from said chamber for work pieces, work conveyor means operative to move work pieces through said chamber from said charging station to said discharge station, heating means for said furnace chamber including a fluid fuel burner located at said discharging station and comprising a combustion chamber with a restricted outlet directed toward the portion of the furnace chamber space occupied by each work piece when moved into said discharge station by said conveyor, means for supplying combustible fluid to said combustion chamber at a relatively low pressure comprising a supply conduit continuously open to said combustion chamber and means for intermittently supplying combustible fluid at a higher pressure to said combustion chamber comprising a supply valve opened and closed by work conveyor means to intermittently maintain a relatively high pressure in said combustion chamber to thereby discharge through said restricted outlet a fluid jet adapted to move a work piece out of said furnace chamber portion and into said discharge passage.
